UNITED STATES PATENT OFFICE.

SILAS H. RANDALL, OF WYOMING, OHIO, ASSIGNOR OF ONE-HALF TO JAMES D. RANDALL, OF SAME PLACE.

LEATHER-PUNCHING MACHINE.

SPECIFICATION forming part of Letters Patent No. 439,603, dated October 28, 1890.

Application filed June 14, 1890. Serial No. 355,469. (No model.)

To all whom it may concern:

Be it known that I, SILAS H. RANDALL, a citizen of the United States, residing at Wyoming, in the county of Hamilton and State 5 of Ohio, have invented certain new and useful improvements in Leather-Punching Machines; and I do declare the following to be a full, clear, and exact description of the invention, reference being had to the accompanying drawings, which form a part of this specification.

This invention relates to those machines which are used by harness-makers for punching a series of holes in leather straps, &c., and 15 the first part of my improvements comprises a novel combination of devices whereby the simple depression of the free end of a treadle causes a cutting-block to descend and hold the work down firmly upon a table of the machine, after which act, a gang of punches is 20 elevated and the strap perforated in a number of places from its under side, as hereinafter more fully described.

The second part of my improvements comprises a novel combination of devices whereby 25 the strap is automatically adjusted upon the table in such a manner as to bring the center of the work in line with the centers of the various punches, as hereinafter more fully described.

The third part of my improvements comprises a novel trip mechanism wherewith certain portions of the machine can be lowered when occasion requires for the purpose of 35 affording convenient access to the gang of punches, as hereinafter more fully described.

My invention further comprises certain improvements in the details of the machine, as hereinafter more fully described.

40 In the annexed drawings, Figure 1 is a front elevation of a leather-punching machine embodying my improvements, said machine being shown in condition for receiving a strap. Fig. 2 is a side elevation of the machine. Fig. 45 3 is an enlarged vertical section of the cutting-block and its accessories. Fig. 4 is a rear elevation of the machine. Fig. 5 is a vertical section of the same. Fig. 6 is an enlarged plan of the table, a portion of the same being 50 broken away and some of its accessories sec-

tioned. Fig. 7 is an enlarged front elevation of the upper portion of the machine, the trip mechanism being liberated and the punch-stock lowered. Fig. 8 is a horizontal section of the machine, taken at the line Z Z of 55 the preceding illustration. Fig. 9 is a similar section taken at the line Z' Z'. Fig. 10 is an enlarged vertical section showing a piece of work clamped upon the table and a punch about to ascend and penetrate the strap. Fig. 60 11 is an enlarged elevation of the lever that operates the parallel clamp-bars of the machine.

The base of the machine consists of a tripod-casting A, to which is secured a pillar or pedestal A', that carries the operative parts of the machine, said pillar being preferably composed of a piece of cold-rolled shafting with a longitudinal groove a along its front upper portion. Projecting from the front of this 65 pillar is a stop a', that serves as the sole support for all the operative parts, said stop being chamfered off on its under side and having normally a screw b in contact with it, which screw engages with a cross-bar connecting the lower ends of a pair of bell-crank B B', pivoted at b' to ears c c', projecting rearwardly from the side bars C C' of a vertical frame, as seen in Fig. 4. b'' is a cross-bar 70 uniting the upper portions of said bell-crank, 75 which devices B B' b constitute the "trip mechanism" of the machine.

The side bars C C' of the vertical frame are united at bottom, as at c'', at top, as at c''', and at intermediate points by braces C''. Furthermore, the extreme lower end of this frame has a guide C''' bearing against the front of pillar A', and in front of this guide a pivot d is located for a pair of treadle-levers D D' to swing upon, the free end of these levers being furnished with a block d' for the operator's foot to press against.

d'' is a set-screw that limits the upward swing of the treadle by bearing against the vertical frame, the top cross-bar of which c''' 95 is pierced to admit a screw-threaded shaft E, which shaft is clamped to said bar by nuts e e' and carries at its lower end an adjustable nut e'', for a purpose that will presently appear. The upper end of this shaft screws 100

into a punch-stock F, which is a casting having at its ends upwardly-projecting lugs $f'f''$, against which a bar G is forced, as more clearly seen in Fig. 8. This bar is tapped to 5 admit screws g, which clamp a bar or a pair of bars $g'g''$ against the shanks h, of a gang of suitable punches H, as represented in Figs. 8 and 10. The main or front bar G is held in place by screws II', engaged with threaded 10 ears i i', projecting from the front of punch-stock F, which latter is connected by side plates F' F'' with a cross-bar J at the extreme upper end of the machine, said bar being provided with a feather j, that traverses the longitudinal groove a of the pillar. (See Fig. 5.) 15 j' is a cap that secures this bar to said pillar. Fitted between these side plates F' F'' are other side plates K K', that connect a vertically-reciprocating head L with a lower section M, said head being furnished with a feather l, traversing the groove a, and a cap l', that secures said head to the pillar. Furthermore, this reciprocating head has a cutting-block N, secured to it by a clamp-bar n 20 and screws or bolts n', said block being in line with the punches H. The lower section M has a feather m, traversing the groove a, and a cap m', that secures said section to the pillar. m'' is a lug projecting from the front 25 of this section, which lug is pierced, as seen in Figs. 1, 5, and 9, to permit a free passage of the screw-shaft E, the latter being surrounded by a powerful coiled spring Y, that pushes against said lug, and the adjusting-nut 30 e'', the object of this spring being to elevate the section M and all its attachments. Section M has a pair of lugs o o, wherewith are engaged the upper ends of rods O O', the lower ends of the latter being pivoted at o' o' 35 to the treadle of the machine. Projecting laterally from this section is a bar P, having a screw p tapped in it, which screw pushes up an extension q of a lever Q, the swing of this lever in the opposite direction being regulated by a screw q', tapped in said extension, 40 which screw q' comes in contact at the proper moment with a lug r of hanger R, within the lower end of which latter said lever is pivoted. This lug is pierced to permit free vertical 45 play of a screw-threaded rod S, whose lower end is secured to the lever-extension q, while its upper end carries a nut s, wherewith is adjusted the tension of a spring s', which has a constant tendency to swing the lever Q 50 away from the hanger R, the latter being pendent from a frame T, as seen in Fig. 2. Frame T has a clamp-screw t to hold a gage-strip t' in place, as seen in Fig. 6. t'' are lugs wherewith said frame is secured to a horizontal 55 table U, the latter being immovably attached to the pillar A by a bolt u or otherwise, and having a longitudinal slot u' of the proper size and shape to admit the upper ends of the punches H. Resting upon this 60 table are two parallel bars V V', connected to links v v at one end of the table and to other links v' v' at the opposite end thereof, an

opening u'' being made in one end of said table to enable said bars to be jointed to small rods W W'. These rods are carried along 70 under the table U and then passed through openings in a shaft w, journaled in the upper end of lever Q, as more clearly seen in Fig. 11. w' w'' are set-screws wherewith said rods are properly secured in said shaft w. 75

Punch-stock F has a feather f'', that traverses the groove a of the pillar, and a cap f''', that attaches said stock to said pillar. (See Fig. 8.)

X in Fig. 10 is a strap or other piece of work 80 to be punched.

In the normal position of my machine the screw b of the trip mechanism rests upon the stop a' of pillar A', thus supporting the vertical frame C C' c' c''', and as the punch-stock F is rigidly connected to said frame by the screw E and nuts e e', said stock is raised accordingly and the top of the punches kept about on a level with the upper surface of table U, as seen in Figs. 5 and 10. Furthermore, in this normal position of the machine the powerful spring Y elevates the lower section M and its integral head L, which motion being communicated by the rods O O' to the treadle D D' causes the latter to assume the 90 position seen in Fig. 2. This lifting of the head L affords sufficient space between the block N and table U for the piece of work X to be readily inserted, the gage-strip t', which is usually of wood, having been first properly 100 adjusted upon said table and held in place by the clamp-screw t. Again, in this normal position of the machine the screw p bears against the extension q, and thus swings the lever Q back until it is about parallel with 105 hanger R, as seen in Figs. 1 and 4. Consequently the rods W W' are shifted toward the left end of table U, the result being to force the clamp-bars V V' away from each other, while at the same time they are maintained in a parallel position by the links v v 110 v' v'. As soon, however, as the treadle is depressed, as indicated by the arrow in Fig. 2, the rods O O' pull down the section M, head L, and bar P, and the instant the screw p is 115 thus lowered with said bar the spring s' swings the free or upper end of lever Q away from the hanger R. The lever is then arrested by the other screw q' coming in contact with the lug r of said hanger, thereby preventing the 120 bars V V' being brought too near together. This outward swing of the lever pulls the bars W W' toward the right end of table U, and in so doing said bars automatically adjust the strap and hold it in line with the centers 125 of the punches, because the bars close up toward each other uniformly and perfectly parallel. Therefore no time is lost in adjusting the work upon the table. The continued descent of the treadle causes the head L to 130 travel down until the cutting-block N rests upon the upper surface of the strap X, as seen in Fig. 10, which illustration shows that the work is now clamped immovably to the

table U. It is apparent the head L can descend no farther, although the treadle has not completed its stroke. Consequently as the treadle continues to be forced down the frame C C' and its attached stock F are raised and the punches H forced through the strap or other piece of work from its under side. This elevation of the frame and punch-stock is due to the fact that when the head L is arrested by the contact of block N with strap X the rods O O' serve as suspenders or slings for the treadle, and therefore the only possible result of further depressing said treadle is to elevate the frame and stock. The position the treadle assumes when it is so depressed as to accomplish this result is indicated by dotted lines in Fig. 2. Upon releasing the treadle the spring Y, acting from the lug m'' of the now stationary part that carries the cutting-block N, forces downward the nut e'', shaft E, punch-stock F, punches H, frame C C', and pivot d until the screw b strikes the stop a'. Then acting from the now stationary bearing e'' the spring Y forces upwardly this lug m'', the section M of which said lug is a part, together with the head L, connecting-rods O O', pivot o', and treadle D until the screw d'' of said treadle strikes the frame C C'; but just before the completion of this upward stroke the screw p strikes the extension q, thereby forcing the lever Q toward the hanger R and parting the guide-bars V V', which motions continue until the ascent of the head L is arrested. In order to change or adjust the punches, the treadle is depressed to bring the block N down upon the table U, and then to slightly raise the punch-stock F and frame C C', thus lifting the screw b from off the stop a', after which act the lower ends of bell-cranks B B' are swung forward until their bottom cross-bar clears said stop and the treadle is thereby released. Frame C C', punch-stock F, and pivot d then descend until the screw d'' again comes in contact with said frame. After the frame and stock are thus lowered, as seen in Fig. 7, the tops of punches H are considerably below the table U, and then by slackening the screws I I' the bar G, to which said punches are attached, can be readily removed from the machine. A bar with other punches attached can now be applied to the stock and secured in place by the screws, and by again depressing the treadle the frame C C' and punch-stock F will be elevated to their previous positions. As this frame ascends, the screw b rides over the chamfered surface of stop a', and when the said frame reaches its proper elevation the bell-cranks B B' automatically swing back and cause said screw to again rest upon said stop. The machine is now in condition to be again operated, as previously described.

It will be apparent that by providing the various moving parts of the machine with feathers that traverse the groove a these parts are free to be raised or lowered, but are in-

capable of swinging around the pillar either to the right or left. Therefore said parts are kept accurately in line with each other without employing an expensive and complicated system of guides, &c. It is also apparent that the frame C C' and punch-stock F might be a single casting; but by making them in separate pieces and uniting them by the screw-shaft E and nuts e e' it is an easy matter to fit up the machine, and enables it to be repaired with the utmost facility.

I claim as my invention—

1. The combination, in a leather-punching machine, of a stationary perforated table, a reciprocating head above said table, a cutting-block secured to this head, a reciprocating punch-stock below said table, a punch fastened to said stock, an extension projecting downwardly from the latter, and a lever fulcrumed to said downward extension and having another fulcrum to a connection coupled to said reciprocating head, substantially as described.

2. The combination, in a leather-punching machine, of a stationary perforated table U u', a reciprocating head L above said table, a cutting-block N, secured to this head, a reciprocating punch-stock F below said table, a punch fastened to said stock, a treadle D D', pivoted at d to a downward extension C C' of said stock, rods O O', connected to said head L and pivoted to said treadle at o', which pivot o' is in front of the pivot d, a bell-crank B B', pivoted to the extension C C' at b', and a fixed stop a', all as herein described, and for the purpose stated.

3. The combination, in a leather-punching machine, of a stationary table, a punch or gang of punches, a lever for operating the latter, a pair of parallel clamp-bars V V', pivoted to the upper side of said table by links v v' v', a vibrating lever Q, pivoted to a fixed hanger R, rods W W', connecting said vibrating lever to said clamp-bars V V', a device that swings lever Q away from hanger R, and a projection P, extending from the lower reciprocating section M, for the purpose stated.

4. The combination, in a leather-punching machine, of a stationary table, a punch or a gang of punches, a lever for operating the latter, a pair of parallel clamp-bars V V', pivoted to the upper side of said table by links v v' v', a vibrating lever Q, operated by a moving part of the machine and carrying at its upper end a shaft w, rods W W', connecting said shaft and clamp-bars, and set-screws w' w'', wherewith said rods W W' are adjusted within said shaft w, all as herein described.

5. The combination, in a leather-punching machine, of a stationary perforated table, a reciprocating head above said table, a cutting-block secured to said head, a reciprocating punch-stock below said table, a punch fastened to said stock, a treadle pivoted to a downward extension of the latter, and a pair of

rods coupled to said head and connected to said treadle between its pivot and free end, for the purpose herein described.

6. The combination, in a leather-punching machine, of a stationary perforated table U u', reciprocating head L, a cutting-block N, attached thereto, a reciprocating stock F, a gang of punches H, applied thereto, a frame C C', extending downwardly from said stock, 5 a treadle D D', pivoted to said frame, rods O O', coupled to said head and connected to said treadle between its pivot and free end, and a spring Y, coiled around a rod E, attached to said frame C C', for the purpose herein described.

7. The combination, in a leather-punching machine, of a stationary perforated table, a reciprocating head, a cutting-block secured thereto, a reciprocating stock, a gang of 10 punches fastened to the same, a treadle that operates said head and stock, a frame C C', extending downwardly from the latter, a pair of bell-cranks B B', pivoted to said frame, and a stop a', projecting from the supporting-pil- 15 lar A', all as herein described.

8. The combination, in a leather-punching machine, of a stationary perforated table U u', a reciprocating head L above said table, a cutting-block N, secured to said head and 20 below said table, a reciprocating stock F, having lugs f f', screw-threaded ears i i', and screws I I', engaged with said ears, a bar G, having screws g, which carry a bar g', punches H, having shanks h, against which shanks 25 said bar g' bears, and a device that operates said stock, all as herein described.

9. A leather-punching machine consisting of the longitudinally-grooved pillar A a, having a stop a', the vertically-shiftable frame 30 C C', having the trip mechanism B B' b and treadle D D' d applied to it, the punch-stock F, attached to said frame carrying a gang of

punches and provided with a tongue f'' and cap f''', the side plates F' F'', connecting said frame with the cross-bar J, having a tongue 45 j and cap j', the head L, having a tongue l, feather l', and cutting-block N, the side plates K K', connecting said head with the lower section M, which latter has a feather m and is supported by a spring Y, surrounding a 50 shaft E, attached to the frame C C', rods O O', connecting said section M with the treadle D D' d, and a fixed table U for the work to rest upon, as set forth.

10. The combination, in a leather-punching 55 machine, of a stationary perforated table, a reciprocating head above said table, a cutting-block secured to the latter, a reciprocating punch-stock below said table, a punch fastened to said stock, a lever-connection for 60 raising and lowering the latter, and a trip mechanism coupled to an extension of said stock and normally bearing against a fixed stop of the machine, substantially as herein described.

65 11. The combination, in a leather-punching machine, of a stationary table, a punch or gang of punches, a lever for operating the latter, a pair of parallel clamp-bars V V', pivoted to the upper side of said table by links v v v' v', a vibrating lever Q, pivoted to a fixed hanger R, rods W W', connecting said vibrating lever to said clamp-bars V V', a spring S', bearing against a lug r of said hanger and coupled to said lever by a rod S, and a bar P, 70 75 projecting from the lower reciprocating section M, all as herein described, and for the purpose stated.

In testimony whereof I affix my signature in presence of two witnesses.

SILAS H. RANDALL.
